US00D629000S

(12) **United States Design Patent**
Zalewski et al.

(10) **Patent No.:** **US D629,000 S**
(45) **Date of Patent:** **** Dec. 14, 2010**

(54) **GAME INTERFACE DEVICE WITH OPTICAL PORT**

(75) Inventors: **Gary M. Zalewski**, Oakland, CA (US);
Colby B. Springer, Sunnyvale, CA (US)

(73) Assignee: **Sony Computer Entertainment America LLC**, Foster City, CA (US)

(**) Term: **14 Years**

(21) Appl. No.: **29/246,764**

(22) Filed: **May 8, 2006**

(51) **LOC (9) Cl.** **14-03**

(52) **U.S. Cl.** **D14/400; D21/333**

(58) **Field of Classification Search** ..... **D14/217, D14/218, 300, 356, 388, 399, 400, 401, 412-416, D14/432, 454-457, 496; D21/324, 332, D21/333, 329, 331; 463/1, 30, 36-38, 46, 463/47; 273/148 B, 148 R; 345/156-161, 345/905**

CLAIM

We claim the ornamental design for an game interface device with optical port, as shown and described.

DESCRIPTION

The single FIGURE is a front view of game interface device having an optical port thereon.

The top plan view is non-claimed subject matter;

The bottom plan view is non-claimed subject matter;

The left side view is non-claimed subject matter;

The right side view is non-claimed subject matter;

The rear view is non-claimed subject matter.

Those portions of the FIGURE illustrated in hashed lines constitute non-claimed subject matter. These portions of the figure do not constitute a part of the claim and are presented solely for context.
